F. SCHNEEBERGER

CARBURETOR

Filed Jan. 9, 1923

Inventor:

Fritz Schneebberger.

UNITED STATES PATENT OFFICE.

FRITZ SCHNEEBERGER, OF BERNE, SWITZERLAND.

CARBURETOR.

Application filed January 9, 1923, Serial No. 611,621, and in Germany October 12, 1922.

This invention relates to a carburetor for internal-combustion engines and of the kind in which the fuel is led from the float chamber to the mixing chamber through the 5 throttle valve.

Fig. 1 of the accompanying drawings represents a vertical section of the carburetor,

Fig. 2, another vertical section taken on the line 2—2 of Fig. 1, and

Fig. 3, a horizontal section taken on the line 3—3 of Fig. 1,

Fig. 4 is a vertical section showing the valve body in a different position to that of Fig. 1,

Fig. 5 is a vertical section showing a valve body of modified construction.

The carburetor comprises a float chamber *s*, a valve casing *a* and a mixing chamber *b*. The valve casing guides a hollow semi-cylindrical valve body *c* adapted to rotate about a horizontal axis when actuated by an operating lever *r*. The valve controls the inlet to the mixing chamber *b* which is arranged tangentially to the same. Atmospheric air is admitted to the mixing chamber along the straight side of the valve, as indicated by the arrow I, the admission, which is regulated by a rotary adjustment of the valve, being dependent upon the distance of the edge *y* of the valve from the edge *z* of the valve casing. In the extreme open position of the valve, additional air is admitted through the valve body, as indicated by the arrow II, the curved wall 30 of the valve body being provided with ports *c*² whose effective area is also regulated by the adjustment of the valve. The valve is formed with a radial chamber which communicates with a central cone *c*¹. A seat 35 which is made for the latter in the casing *a*, communicates through a duct *f* with the float chamber which thus maintains the fuel at a level *x* in the radial valve chamber. The nozzle *d* which terminates the chamber 40

45 is situated at the circumference of the valve body, near the edge *y* so as to be traversed by the current of the incoming air. There is also a duct *e* leading from the lower part of the chamber to the circumference of the valve body and opening at a point near the port *c*². The valve chamber communicates with the atmosphere through a narrow duct *g* opening at the front of the valve body *c*.

In all positions of the valve body, the air current I will pass over the nozzle *d* with the greatest velocity and ensure an effective atomizing of the fuel. Fig. 1 shows the valve wide open. The air currents I and II meet over the spraying nozzle and mix thoroughly with the atomized fuel. It will be noticed that the distance *h* from the nozzle *d* to the surface *x* of the fuel will vary with the angular position of the valve. The fuel supply will vary accordingly, the mixture being weakened as the valve is being opened.

With the valve in the position shown in Fig. 4 the direct air admission is closed, and the duct *e* communicates with the mixing chamber through a duct *m* in the valve casing. The nozzle *d* is situated near the level of the liquid and outside the valve casing so that air will be sucked in through the nozzle and led, together with the necessary fuel, through the ducts *e* and *m* to the mixing chamber. The capacity of the duct *m* can be regulated by means of a screw *k*.

A still further adjustment of the valve body to the right, sets the nozzle body *d*¹ 80 free so that it can be unscrewed for cleaning or for renewal.

The valve body *c* is inserted axially into its seat and is held in position by a spring *o* which can be turned aside without tools so as to release the valve and allow it to be removed from the casing.

In the modified construction of the valve according to Fig. 5, the nozzle *d* is situated outside the valve body and forms the only 90 communication of the fuel supply with the mixing chamber *b*. The orifice is situated somewhat below the edge *y* within the circumference of the valve body. While the valve is closed, as shown in Fig. 5, the motor 95 will act as a brake, for instance while the machine is running down-hill.

I claim:—

1. In a carburetor of the character described, a hollow semicylindrical valve body 100 having a fuel nozzle arranged radially along its straight side and circumferential distanced ports, a casing holding the valve body rotatively and allowing it to be inserted and withdrawn in axial direction, 105 means for retaining the valve body in position, the casing being adapted to admit atomizing air into the mixing chamber past

the straight side of the valve body in all open positions of the latter and additional air through the ports of the valve body only in the fully opened position of the same, one wall of the mixing chamber being arranged tangentially to the casing so as to lead the atomizing air across the fuel jet.

2. A carburetor having the features claimed in claim 1 and in which the means for holding the valve body in position consists of a spring arranged so that it can be turned aside by hand for releasing the valve body.

FRITZ SCHNEEBERGER.
